UNITED STATES PATENT OFFICE.

SADIE STUCKEY, OF TULSA, OKLAHOMA.

ELECTRIC HAIR-CURLING KIT.

1,273,199.

Specification of Letters Patent.

Patented July 23, 1918.

Application filed July 10, 1917. Serial No. 179,689.

To all whom it may concern:

Be it known that I, SADIE STUCKEY, a citizen of the United States, residing at Tulsa, in the county of Tulsa and State of Oklahoma, have invented certain new and useful Improvements in Electric Hair-Curling Kits, of which the following is a specification.

The invention has for an object to provide a hair curling kit including an electric heater requiring no special support, but which may be set upon any flat horizontal surface and utilized for heating an iron and curling the hair. It is an important object to give an appliance of this character which may be folded very compactly, and to so construct the iron and heater element that they will coact and contribute to form a unitary outfit, the parts of which will not become detached casually, so that they will always be found together and there will be a minimum liability of their separation or the loss of one of the parts from the other. It is an important object particularly, to give a satisfactory form of construction in the curling iron whereby it may be easily folded, and will be securely retained in open position when desired.

Additional objects, advantages and features of invention will appear in the construction, arrangement and combination of parts hereinafter described and shown in the drawings, wherein,

Figure 1 is an elevational view of the kit in closed position,

Fig. 2 is a similar view of the device ready for use in curling hair,

Fig. 3 is a detail of the pivotal and fastener construction of the curling iron,

Fig. 4 is a cross sectional view of the heater,

Fig. 5 is an end view of one embodiment of the heater,

Fig. 6 is a detail of one of the possible pivotal connections for the supporting brackets of the heater.

Fig. 7 is an elevation of the complete device in a modified form, folded.

Fig. 8 is a longitudinal sectional view of the barrel of the heater.

Fig. 9 is a detail of the core element of the heater, detached.

There is illustrated a hair curling kit comprising a heater 10, and a curling iron 11. The heater comprises an inner cylindrical 55 casing section 12, having at one end the flange 13 with an inturned edge portion 14, parallel to the cylindrical body 12. An outer cylindrical casing section 15 is also provided, having an inwardly directed flange 60 16 at one end, with an inturned cylindrical edge portion 17, parallel to the part 15. The edge portion 14 of the first mentioned section is of a diameter to fit the cylinder 15 snugly, while the inturned edge portion 17 65 (see Figs. 8 and 9) is of a diameter to fit snugly around the end of the cylinder 12 opposite the flange 13. Around the cylinder 12 there is disposed a suitable insulation 18, upon which a suitable heating coil 19 is 70 wound, a body of insulating material 20 being disposed outwardly thereof within the cylinder 15. The ends of the coil are connected to suitable wires fixed in proper bushings 22 in the flange 14 of the inner 75 section of the heater casing. These wires are of customary length, and have at their outer ends an ordinary attaching plug 23, adapted to be screwed in the usual lamp socket.

80
Adjacent each end of the heater, and on each side, there are secured pivot lugs 24, each having a central recess 25, receiving the inturned extremity 26 of a wire bracket bail and support 27, formed of resilient wire 85 under tension by which its extremities bear inwardly upon respective pivot lugs, there being two of the bails, located adjacent respective ends of the heater with arms located on opposite sides of the heater and engaged 90 with the respective adjacent pivot lugs. All of the lugs are formed with grooves in their outer faces extending from the central aperture at right angles to the heater in one direction, so that when the bails are moved to 95 their outermost position, their arms may snap into these grooves and be held yieldably against oscillation. Adjacent the inner ends of the grooves, and on the inner sides of the lugs, toward the central part of the 100 heater, there are formed spiral cam faces 28, inclined downwardly toward the side of the heater casing, and beginning outwardly of the recess and intermediately of one side of

- the groove, so that after the respective bail has been moved inwardly toward the middle of the casing a short distance, it will engage upon the cam face, and by the resilient action of the bail arm be forced farther inward, for a purpose which will be explained. The outer parts of the bail have U-shaped bight portions 29, bent at right angles to a plane including the inner parts of the arms of the bails, toward the casing, so that when the bails are in their extended position the bights will lie in a plane parallel to the casing of the heater, and serve to support it steadily upon any flat horizontal surface. The bight portions are sufficiently extended to receive and hold therewithin the curling iron 11, when folded and laid against the central portion of the heater casing, and the bails moved inward. By the action of the bail arms on the cam face before mentioned, the bails will be forced inwardly against the curling iron, so that it will be held snugly against casual detachment. The curling iron comprises a handle 31, in which there is suitably fixed a shank stub 32, bifurcated at its outer part and slightly curved toward one side. Pivoted between the furcations of this shank there is a tongue 33, formed on the body 34 of the curling iron, which comprises a bar of metal of suitable thickness and length, having its inner end curved slightly, immediately adjacent its pivot, so that when the iron is in extended position the inner curved part will project slightly in the same direction as the curved part of the shank 32. By this formation, the curling iron body may be folded inwardly to lie snugly and flatly against the handle portion when desired, and when moved to outermost position the curved part of the iron proper and the curved part of the shank 32 will extend at a slight angle to each other, as shown in Fig. 2. Both the shank 32 and the tongue 33, are formed with notches 34', positioned to lie in transverse alignment when the iron is in extended position, and suitably secured in relation to the shank 32 there is a spring 36, having an inturned bill 37, and under tension tending to force the bill into the alined notches, so that when the iron is moved into extended position the spring will snap into the alined notches and prevent further relative movement of the parts until the spring is lifted. In this manner, an extremely light metal tongue is made available for holding the parts of the iron against pivotal movement and resisting considerable force tending to move the body of the iron on its pivot. The spring is formed with a suitable bill 37 on its outer part, adapted to receive a finger nail thereunder by which it may be lifted. Before use, the kit is normally in closed con-

dition, the iron 34 being folded against the handle 31 and retained under the bails 27. If desired, the handle may be formed with small notches 38 on the sides thereof into which the bails may fit snugly whereby longitudinal movement of the iron under the bails will be prevented positively. When it is desired to curl hair with the device, the supporting bails of the heater are simply pulled to their extended positions, when they will snap into the grooves before mentioned and be held in proper extended relation. This frees the iron, which is removed and pulled to open position, the spring automatically snapping into engagement to hold the parts in extended order. The heater being set upon a suitable supporting surface the plug 23 is screwed into an adjacent lamp socket, after which the current is turned on to heat the device. The iron is inserted within the heater, the size of the inner cylinder of the casing being very slightly larger than the iron 34, so that the latter may fit snugly and slidably therein, in which manner the iron is properly supported without requiring any brackets or other supports beneath the handle. The iron may be used in curling hair in any of the familiar methods ordinarily practised.

In Figs. 5 and 7 there is illustrated a form of device in which the bail elements are so shaped at each side that when moved into closed position, the inner portions 27' will project above the center of the barrel 15' and these parts are curved inwardly as shown in Fig. 5 so as to bear against the barrel, holding the bails yieldably against outward movement, in addition to the effect of the cam portion on the pivot lug before described. This will make the retention of the curling iron doubly secure. In Figs. 5 and 7 the parts corresponding to those first described are indicated by like numerals, with the addition of prime marks.

What is claimed:

1. A device of the character described comprising a tubular cylindrical heating element, longitudinally spaced supporting elements thereon having transverse portions adapted to bear toward the side of the heater element when the supports are moved inwardly, means tending to cause the supports to move to innermost positions, and a curling iron constructed to engage snugly against the side of a heater element within said transverse portion for retention thereby.
2. In a device of the character described a heater device comprising a tubular cylindrical casing, an electrical heating means therein, a plurality of pivot lugs on the side of the casing including grooved parts extending in one direction and spiral cam portions at their inner sides, and bail members of resilient material including arms having inturned portions and engaged in

said lugs, said arms being under tension to bear yieldably against the lugs, and constructed to engage snugly in said grooves in one position, and to engage on said spiral 5 cam portion at another position, whereby the bails will be moved inwardly and held in closed position.

In testimony whereof I have affixed my signature in presence of two witnesses.

SADIE STUCKEY.
